UNITED STATES PATENT OFFICE

126,853

DESIGN FOR A BUILDING

Isaac J. Leavitt, Denver, Colo.

Application May 24, 1940, Serial No. 92,574

Term of patent 3½ years

To all whom it may concern:

Be it known that I, Isaac J. Leavitt, a citizen of the United States, residing at Denver, in the city and county of Denver and State of Colorado, have invented a new, original, and ornamental Design for a Building, of which the following is a specification, reference being had to the accompanying drawings, forming part thereof.

Fig. 1 is a front elevational view of a building showing my new design; and

Fig. 2 is a top plan view thereof.

Each end of the building is a continuation of the design of the front of the building adjoining such end. The rear is plain.

I claim:

The ornamental design for a building, as shown and described.

ISAAC J. LEAVITT.
